(57) **CLAIM**

The ornamental design for a digital multi-function electric gauge, as shown and described.

DESCRIPTION

FIG. 1 is a perspective view of a digital multi-function electric gauge showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof.

FIG. 8 is another perspective view showing the digital multi-

function electric gauge; and,

FIG. 9 is a perspective view showing another embodiment of

the digital multi-function electric gauge.
